UNITED STATES PATENT OFFICE.

JOHN V. CUNHA, OF BERKELEY, CALIFORNIA, ASSIGNOR TO THE PARAFFINE COMPANIES, INC., OF SAN FRANCISCO, CALIFORNIA, A CORPORATION OF DELAWARE.

SATURATING APPARATUS.

Application filed May 29, 1920. Serial No. 385,147.

To all whom it may concern:

Be it known that I, JOHN V. CUNHA, a citizen of the United States, and a resident of Berkeley, county of Alameda, and State 5 of California, have invented a new and useful Saturating Apparatus, of which the following is a specification.

My invention relates to apparatus for saturating roofing fabrics.

10 An object of the invention is to provide an apparatus capable of thoroughly and uniformly impregnating or saturating roofing fabrics with a waterproof compound such as asphaltum.

15 Another object of the invention is to provide an apparatus of the character described which operates at a speed sufficient to enable it to keep pace with the coating operations which are much faster normally than

20 previously known saturating processes. This permits fabric from the saturating apparatus to be run directly through the coating apparatus, the fabric moving through both, at the highest permissible speed.

25 The invention possesses other objects and features of advantage, some of which, with the foregoing, will be set forth in the following description of the preferred form of my invention which is illustrated in the

30 drawings accompanying and forming part of the specification. It is to be understood that I do not limit myself to the showing made by the said drawings and description, as I may adopt variations of the preferred 35 form within the scope of my invention as set forth in the claims.

In the drawings, Figure 1 is a plan view 40 of the apparatus of my invention and Figure 2 is a side elevation thereof. Both views are partially in diagram. Figure 3 is an elevation in diagram showing the saturating drums and tank. Figure 4 is a side elevation of the tension controlling means including idler pulley 17.

45 From the supply roll 2 suitably mounted for rotation in frame 3, the web 4 of roofing fabric passes around the smooth brake cylinders 5, stationary in the frame 6, so as to give a certain tension to the web, 50 and then around heating drums 7 and 8 through which live steam is circulated by well known means, comprising pipes 10 connected axially with the drums by means of the usual rotary couplings. While on the heating drums, the moisture in the fabric is

turned to steam and driven off leaving the felt quite dry and in an expanded condition, which greatly facilitates the penetration of the saturating compound. The heating drums are provided at one end with meshed 60 gears 9, the upper one of which is turned by a pinion on shaft 11, which is connected by miter gears 12 to the jack shaft 13, driven from the main shaft 14 by belt 16. An idler pulley 17 is arranged in a frame 18 against 65 one reach of the belt. The frame is vertically adjusted by a suitably arranged screw 19 to vary the slippage of the belt, so that the speed of the drums relative to the speed of the main shaft may be adjusted to a 70 nicety. The size of the parts is such that if there were no slippage of the belt 16, the drums would rotate a trifle faster than the normal operating speed of the machine. The idler 17 however is adjusted so that the 75 slippage is such as to drive the heating drums a trifle slower than the succeeding portions of the machine so that the desired degree of tension is maintained on the web. Different materials and saturating com- 80 pounds necessitate different adjustments of the idler to vary the slippage but once properly adjusted for a given material and compound, the tension of the web through the entire subsequent portions of the machine is 85 determined and controlled.

Adjacent the heating drums are a series of saturating drums 21, 22, 23, 24, 25, 26, and 27, over and around which, the web passes in the order named. These drums are also 90 heated by live steam in the same manner as are the heating drums, and it is while on them that the web is thoroughly and uniformly saturated with the waterproof compound, which is preferably asphaltum.

The saturating drums are connected for rotation together by gears 28 fixed on their shafts. The gear on drum 21 is meshed with the gear on drum 22 which is also meshed with the gear on drum 23 and so on 100 through the series of drums which thus all turn in the proper direction and at the same speed. The train of gears 28 is driven by a pinion on shaft 29 arranged above drum 26 and turned by driving gear 31 connected by 105 chain 32, jack shaft 33, and chain 34 to sprocket 36 on the main shaft.

Below the saturating drums is a tank for the saturating compound, divided by a partition 37 into two compartments 38 and 39, 110

compartment 38 underlying drum 21. A valved by-pass 41 connects the two compartments so that if desired they may be placed in communication, the saturating compound 5 then rising to the same level in each. For certain kinds of work, this is done, but usually the by-pass is closed and the compartment 38 kept full of compound, the surplus running into the compartment 39 over the 10 edge of the partition. The compartments contain steam coils 42 for keeping the compound hot, and a very important portion of my invention is comprised in the conception of and means for circulating the compound 15 through the tank and over the webs on the drums. Over drums 22 and 24 are arranged troughs 43 and 44 respectively, into which saturating compound from the front end (right of Figure 3) of compartment 39 is 20 pumped by means of pipe 46 and gear pump 47. The troughs are inclined so that the compound spills over the edge evenly upon the web on the drum below as shown in Figure 3. The surplus compound from trough 25 43 drains into compartment 38, and keeps it full to the edge of the partition 37. The surplus compound from trough 44 drains into compartment 39. Thus a continual circulation of saturating compound is maintained 30 through the tank and over the heating coils therein, part of the circuit comprising cascades of the compound upon the upper surface of the web as it passes over the drums. The means, just described maintains 35 a homogeneous compound, and at substantially the same temperature at all points so that varying conditions of density and temperature are avoided. A high quality of product cannot be secured if these factors are uncertain and varying, and I have been able by the means set forth to reduce them to known quantities and maintain them substantially constant. With the by-pass open, the lower portion of each drum 40 is immersed in the compound, but this is desirable only with certain kinds of fabric, and ordinarily I close the by-pass, maintaining the first compartment 38 full and the second compartment at a lower level, so 45 that only the first drum 21 is immersed in the saturating compound. Thus the web is immersed in the compound of the first compartment, as it runs under the drum 21, and since compound is pouring down over the 50 web from the trough 43, compound is also carried around the drum between it and the web. This also occurs with each of the other drums, so that a thorough saturation of the fabric is effected. As the web leaves 55 the last drum 27, it passes over a stationary scraper roll 48 which removes surplus compound adhering to the web, especially if the last roll is immersed in the compound. From time to time as needed, additional compound 60 is pumped into the tank through the con-

ductor 49 from a suitably arranged source of supply.

The web next passes through the coating apparatus, in which the surface of the impregnated fabric is covered with a finely divided mineral matter. This coating prevents sticking of the roofing in the rolls, and also contributes toward its wearing qualities. Since this portion of the complete apparatus is of known construction, I will not describe it in detail nor show it in the drawings. 75

After leaving the coating apparatus, the web is wound into rolls 51 of convenient size for marketing. 80

I claim:

1. In a saturating apparatus, a tank adapted to hold a saturating liquid, a series of drums upon which the web to be saturated is carried through the body of said liquid, a second series of drums upon which said web is carried and arranged above said first series, and means for flooding the web with liquid from said tank as it passes over said upper drums. 90

2. In a saturating apparatus, a tank adapted to hold a saturating liquid, means for heating the liquid, a series of drums upon which the web to be saturated is carried through the body of said liquid, means for heating the drums, and means for flooding the web on the upper portion of the drums with liquid from said tank. 95

3. In a saturating apparatus, a tank adapted to hold a saturating liquid, a series of drums upon which the web to be saturated is carried through the body of said liquid, a trough arranged above one of said drums at one end of the tank, means for forcing liquid from the other end of the tank into said trough whereby the overflow therefrom floods the web on the upper portion of said drum, and means for rotating said drums. 100

4. In a saturating apparatus, a tank adapted to hold a saturating liquid, a partition dividing said tank into first and second compartments, a drum upon which the web to be saturated is carried through the body of the liquid in the first compartment, a second drum upon which said web is carried arranged above the first named drum, a series of other drums upon which said web is carried and arranged above the second compartment, a trough arranged above said second drum, means for forcing liquid from the opposite end of the second compartment into said trough whereby the overflow therefrom floods the web on the second drum and the top of the first drum, means for heating the liquid in said tank and means for rotating said drums. 115

5. In an apparatus for saturating a fibrous web, a tank adapted to hold a saturating liquid, a drum immersed in the liquid 120

130

- of said tank, upon which the web to be saturated is carried through the body of said liquid, a second drum upon which said web is carried arranged above said first drum, 5 means for flooding the web with liquid from said tank as it passes over said second drum, and means for drying and expanding the fibrous web before it enters said liquid.
6. In a saturating apparatus, a tank adapted to hold a saturating liquid, a series of 10 drums upon which the web to be saturated is carried through the body of said liquid, heating drums about which said web passes before contact with said saturating drums, 15 means for rotating said drums and means interposed between said heating drums and said driving means for adjustably retarding the rotation of the heating drums.
7. In a saturating apparatus, a tank adapted to hold a saturating liquid, a series of 20 drums upon which the web to be saturated is carried through the body of said liquid,

heating drums about which said web passes before contact with said saturating drums, and means for rotating said drums including 25 means for permitting a predetermined amount of retardation in the rotation of the heating drums.

8. In a saturating apparatus, a tank adapted to hold a saturating liquid, a series of 30 drums upon which the web to be saturated is carried through the body of said liquid, heating drums about which said web passes before contact with said saturating drums, a main shaft, driving gear connecting said 35 shaft with the saturating drums, driving gear including a belt connecting said shaft with said heating drums, a pulley engaging one reach of said belt, and means for varying the position of said pulley to vary 40 the slippage of said belt.

In testimony whereof, I have hereunto set my hand.

JOHN V. CUNHA.
